Fig. 3

Fig. 4

Fig. 5

Fig. 6

Fig. 7

FIG. 1 is a perspective view of a combined baby bed and storage unit embodying my new design;

FIG. 2 is a further perspective view thereof with various openable panels in open positions and removable panels in exploded positions;

FIG. 3 is a side elevational view thereof;

FIG. 4 is a top plan view thereof;

FIG. 5 is a bottom plan view thereof;

FIG. 6 is a front elevational view thereof; and

FIG. 7 is a rear elevational view thereof.

I claim:

The ornamental design for a combined baby bed and storage unit, substantially as shown and described.
